Claims priority, application Switzerland Dec. 21, 1959

5 Claims. (Cl. 139—82)

This invention relates to heald frame holders for looms with lateral suspension of the heald frames (or shafts). It is known to provide the vertical side supports of the frames each with projecting undercut lugs on which a heald frame engages by means of two notch-engaging noses. The support lugs on either side of the heald frames are at a fixed distance from each other. In the prior art embodiment, the holders are each furnished with two notch-engaging noses which are likewise at a definite fixed spaced relation adapted to the two support lugs on the heald frames such as shown for instance in the British Patent No. 542,902. In order to prevent play as far as possible in the upward and downward movements of the heald frames, it is necessary to adapt the lugs and notch-engaging noses accurately to one another. This requirement being very difficult to satisfy in actual practice, a certain amount of play is frequently found likely to manifest itself very adversely at high loom speeds, in that the amount of play gradually increases, because of lugs and notch-engaging noses becoming worn.

This difficulty becomes more serious due to the fact that a certain holder should fit a large number of different heald frames, since the frames are interchangeable, whereas the holders remain in the machine.

Therefore, instead of a form-locking coupling, also a force-locking coupling has already been adopted in that the aforesaid play between the lugs and notch-engaging noses was nullified by a spring, such as shown in the British Patent No. 453,346. However, this coupling was found less suitable for transmitting big inertia forces.

Now the present invention relates to a heald frame holder in which the described disadvantages are obviated with certainty. The holder is principally characterized in that only one notch-engaging nose thereof is arranged in a fixed position, while the other notch-engaging nose is movably designed and can be pressed against the associated lug of the heald frame by means of a toggle clamping device. Moreover, the invention permits of adjusting the vertical position of the heald frames from an easily accessible point without the heald shaft drive having to be slackened. Such devices for adjusting the vertical position are known per se, but they do not lend themselves to combination with the aforesaid toggle clamping device.

Now this is possible with the device according to the invention in that it includes, in accordance with a further feature, a clamping device adapted to secure the heald frame to the drive (or motion) by a device for fine adjustment of the vertical position of the frame.

Further features of the invention will appear from the following description and claims, taken in conjunction with the accompanying drawing which shows purely by way of example two forms of embodiment incorporating the invention.

In said drawing:

FIG. 1 shows a front view of the end of a heald frame with the laterally arranged lugs for fixing the same;

FIG. 2 is a front view and part-vertical section of a heald frame holder according to the first form of embodiment, and the adjacent part of a heald frame;

FIG. 3 is a part-front view and part-vertical section of a heald frame holder and the adjacent part of a heald frame;

2

FIG. 4 shows an end view from the right in FIG. 3 of the heald frame holder alone, on a larger scale.

Referring to said annexed drawing, the heald frame 1 illustrated in FIG. 1 possesses at both ends 2 (one only shown) an upper lug 3 and a lower lug 4, each with a notch 5 and 6 respectively for fixing the heald frame to the holders.

Each of the two holders 7 (one only shown in FIG. 2) includes a tubular rail 8 of rectangular cross-section with a slot-like opening 9 for the entry of the lugs 3 and 4 of the heald frame. A rod 11 representing the upper end of the heald shaft drive is firmly connected to said rail 8, as by rivets 10. The lower end of the rod 11 is connected to the heald shaft driving arrangement.

The rail 8 has arranged therewith a tubular rail 12 likewise of rectangular cross-section. The two rails 8 and 12 each have a lug 8a and 12a, and each of said lugs having longitudinally tapped holes 8c and 12c, respectively. A set-screw 13 is arranged in said longitudinally tapped holes 8c and 12c for adjusting the rail 12 with respect to the rail 8. Two nuts 14 and 15 serve to secure them in position to prevent inadvertent turning of the screw bolt 13.

The lower end of rail 12 has fixed thereto by rivets 17 25 a notch-engaging nose 16 for engaging in the lug 4 on the side 2 of heald frame 1.

The top part of rail 12 has pushed therewith a two-part rod 18 which is linked to the rail 12 through two levers 19, 20 in that the levers 19 at one end is pivoted to the rod 18 and at the other end to lever 20 which, in turn, is pivoted with a pin 20b in the pivotal hole in the lug 12b on rail 12. The rod 18 possesses at its bottom end a notch-engaging nose 21 for engaging through the slot 9 and 12d opening on the outer rails 8 and the inner rail 12 respectively the lug 3 on the side 2 of heald frame 1. The length of the two part rod 18 of rectangular cross-section may be changed by a set-screw 22 forming a part thereof and fixed by a lock nut 22a on screw 22. The adjacent ends of said two longitudinally arranged parts of rod 18 are similarly tapped.

The action of the described heald frame holder is as follows:

Let it first be assumed that the holder 7 is separate from the associated frame 1. On joining the frame 1 to the holder 7, at first the notch 6 of lug 4 on the frame is brought into engagement with the associated notch-engaging nose 16 of holder 7, while the rod 18 is brought into its topmost position by raising the hand lever 20 by means of levers 19. By lowering the hand lever 20, the notch-engaging nose 21 of rod 18 engages the notch 5 in lug 3.

Inasmuch as the spacing between the lugs 3 and 4 is not constant for all frames, and also may change in the course of time due to wear, the frames may be mounted on the holders free from play by suitably adjusting the length of rod 18 by means of the screw 22.

In order to adjust the vertical position of the heald frame, the nuts 14, 15 are slackened, whereupon by turning the screw bolt 13, the clamping device with the heald frame 1 may be changed in relation to the rod or heald drive shaft 11 without the clamping device having to be released.

In the second form of embodiment according to FIG. 3, a heald frame 110 is of conventional design. Each end of the frame has two notched lugs 111 and 112. Each 65 of the holders (one only shown in FIGS. 3 and 4) includes a rail 113 of substantially U-shaped section, whose lower end is coupled to a vertical tie-rod 114. The rod 114 is rigidly secured to the rail 113, as by rivets 115. The top 70 of rod 114 is designed as a notch-engaging nose 116 which engages a suitable notch in lug 112. The bottom of rod 114 is joined to the means for driving the heald frame.

The upper end portion of the guide rail 113 has a slide 117 arranged therein for lengthwise movement. The slide 117 exhibits an elongated slot 118 engaged by a pin 119 which is fixed to the flanges of the guide rail 113 and serves for guiding the slide 117. The bottom end of slide 117 is designed as a notch-engaging nose 120 which may engage a suitable notch in lug 111.

The upper end of slide 117 has welded thereto a bolt 121 possessing a screw-threaded portion. The latter is engaged by an internally threaded sleeve 122 which is supported in a guide tube 123 for longitudinal adjustment.

Both the tube 123 and the top of guide rail 113 are firmly connected to a carrier plate 124 having the guide lug 126 for the heald frame holder affixed thereto by rivets 125. The parts 113, 114, 123, 124 and 126 together constitute the holder body.

The bolt 121 is encircled by a coil compression spring 127 which, with one end, bears against the slide 117 and with the other end against the guide tube 123. Said spring 127 tends to push the slide 117 downwards into its effective position. By means of a hinge pin 128, the top end of the threaded sleeve 122 is joined to a link 129 which, in turn, is connected through a toggle joint pin 130 to a clamping lever 131. Link 129 and clamping lever 131 together constitute the toggle arrangement. The clamping lever 131 comprises two parallel legs having the link 129 pivoted therebetween. The two legs of the clamping lever 131 have between them a cross-pin 132 arranged to press against a nose 133 on the carrier plate 124. At the top the clamping lever 131 also has between its legs an abutment piece 134 which is provided for resting on a stop face 135 of the carrier plate 124.

The action of the described heald frame holder is as follows:

Let it first be assumed that the holder is separated from the associated heald frame 110. On joining the frame to the holder, at first the lug 112 is brought into engagement with the associated notch-engaging nose 116. As the slide 117 is moved upwards by pull on lever 131 against the action of spring 127, the upper lug 111 of heald frame 110 is pushed into the guide rail 113, whereupon release of lever 131 causes the notch-engaging nose 120 of slide 117 to become engaged with lug 111 by action of spring 127. This results in a provisional connection between frame and holder.

The frame 110 is then mounted on the holder free from play by rocking the clamping lever 131 so as to cause the toggle joint pin 130 to move towards the guide lug 126. Subsequent to this, the crosspin 132 may be engaged with the underside of nose 133. Then the top of clamping lever 131 is pressed against the guide lug 126, thus causing said lever 131 to turn about the crosspin 132 and the toggle joint pin 130 moves away from the guide lug somewhat beyond the dead center position until the abutment piece 134 of the clamping lever lies against the stop face 135 of carrier plate 124, thus limiting the pivotal movement of lever 131 in its clamped position. Through toggle action of the parts 129 and 131, the threaded sleeve 122 with the bolt 121 is pressed downwards and thereby the slide 117 firmly pressed against the lug 111 to thus mount the frame 110 free from play in the holder.

In order to remove the frame 110 from the holder, the clamping lever 131 is swung away from the guide lug 126, whereby the toggle action is discontinued, whereupon the crosspin 132 of the clamping lever may readily be disengaged from the nose 133. Then it is possible, again with the aid of lever 131, to withdraw the slide 117 upwards against the action of spring 127, whereby the notch-engaging nose 120 moves clear of lug 111.

With the toggle arrangement in the released position last described, the crosspin 132 of lever 131 may be brought into engagement with the upper surface of the nose 133. The spring 127 then securely holds the lever 131 in said position. In this way it is possible to secure

against inadvertent movement the clamping levers of such holders as do not mount frames for certain weaving operations, in order thereby to prevent mutual interference between the clamping levers of adjacent holders.

Since the spacing between lugs 111 and 112 is not constant for all heald frames and may even change in the course of time due to wear, possibility of readjusting the toggle arrangement is given by suitably turning the threaded sleeve 122 on the threaded portion of bolt 121. Thereby the distance of the hinge bolt 128 from the slide 117 changes according to the pitch of the thread. No tool is required to adjust the threaded sleeve 122, it merely suffices to turn the lever 131 after disengaging from the nose 133.

In a modification (not shown), the connection between slide 117 and hinge bolt 128 of the link 129 is not adjustable. In that case the nose 133 could be adjustably mounted on the plate 124 by means of a set-screw in spindle form in order to make possible adjustment of the position of the notch-engaging nose 120 in the tensioned position of the toggle linkage 129—130, for adaptation to the associated lug 111.

It is understood that other changes and modifications may be made in the embodiments illustrated and described herein without departing from the scope of the invention as defined by the following claims.

What I claim is:

1. In a loom having a heald drive shaft, an adjustable heald frame holder for holding rectangular heald frames of variable sizes, said frames individually having opposite ends and two similar outwardly-extending lugs spaced symmetrically apart on each of said frame ends, each said frame lugs having a notch defined therein, said notches of the same end being oppositely directed, and said frame holder comprising two identical sides for holding each said frame end, each said identical part comprising: rail means having two ends and secured by one said end to the drive heald shaft for being driven thereby; opposed notch-engaging noses attached to said rail means and spaced longitudinally apart to respectively cooperating with and engage in said oppositely directed and spaced notches of said notched frame lugs, one said nose being rigidly fixed, and the other said nose being longitudinally movable in said rail means with respect to said fixed nose; linkage means for slidably actuating said movable nose to lock and release said noses and said notches; and screw means for longitudinally moving said movable nose to adjust the space between said longitudinally spaced apart projections in order that said noses fully engage in said respective frame lug notches to immovably lock said noses in said notches, whereby each side of said heald frame holder is adjustable to engage the sides of a variety of heald frames having variably spaced lugs.

2. An adjustable heald frame holder as described in claim 1 characterized in that said rail means comprises: two tubular rails of rectangular cross section and adapted to engage telescopically, one said rail being the outer rail having two oppositely disposed outer rail ends with one said outer rail end being secured to said heald drive shaft, said outer rail having a longitudinal slot-like opening intermediate said one and the other outer rail ends for the entry therein of said frame lugs, and the other said rail being the inner rail having two oppositely disposed inner rail ends with one said inner rail end telescoping to a position adjacent said one outer rail end and having said rigidly fixed nose attached to said one inner rail end and facing away therefrom opposite a portion of said slot-like opening for the full engagement of said rigidly fixed nose in one frame lug notch, and the other said end on one side having a lateral lug extending outwardly therefrom, said lateral lug having a transverse pivot hole; engaging means on the other ends of said outer and inner rails for adjustably engaging and positioning said inner rail and rigidly attached nose with respect to said outer rail and a notched frame lug extending there-

in; a length-adjustable rod means having oppositely disposed ends, slidably mounted in the other end of said inner rail, said one length adjustable rod end extending outwardly therefrom and the other length adjustable rod end defining said longitudinally movable nose; a hand lever having two oppositely disposed lever ends pivoted at one said lever end in said tapped hole in the lateral lug of the inner rail and pivotally linked intermediate said lever ends to said one end of said length-adjustable rod for longitudinally moving said length-adjustable rod and said movable nose in said inner rail with said handle lever means to a fully engaged position in the other frame lug notch thereby locking both said noses in respective frame lug notches and to a fully disengaged position from said other frame lug notch, thereby unlocking both said noses and said frame end from said holder side.

3. An adjustable heald frame holder as described in claim 2 characterized in that said engaging means on the other ends of said inner and outer tubular rails comprises: a lateral lug extending outwardly on said outer rail and tapped longitudinally; a similar lateral lug extending outwardly on said inner rail and similarly tapped; a screw bolt engageable in said longitudinal taps of said lateral lugs for longitudinally positioning the inner tubular rail with respect to the outer tubular rail; lock nuts on said screw bolt between said inner and outer rail lugs, said nuts for rotation to respectively contact said lugs and lock said screw bolt with the lugs and integral rails in relative position for engaging said one said frame lug notch.

4. An adjustable heald frame holder as described in claim 2 characterized in that length adjustable rod means comprises: a two part rod of rectangular cross section having its parts longitudinally arranged in extension of the other and adapted to slidably engage in said inner tubular rail, the adjacent ends of said two longitudinally arranged parts being similarly tapped; a screw threaded for its full length to simultaneously engage the tapped ends of said two part rod, the length of said two part rod being established by the rotation of said screw and the unengaged length of said screw intermediate said long arranged parts; a lock nut on said screw intermediate said parts for rotation to contact a said part and lock said screw against rotation whereby said two part rod means is lockably adjustable in length when said hand lever means is moved to said fully engaged position for said longitudinally movable nose to fully engage one said frame lug notch when the said fixed nose is fully engaged in the other said frame lug notch.

5. An adjustable heald frame holder as described in claim 1 characterized in that said rail means comprise: a rail of substantially U-shaped cross sections and having

two oppositely disposed ends, said heald drive shaft being rigidly attached to one said rail end and in continuance thereof, and said heald drive shaft defining said fixed nose at said attached end; a slide having two ends and a longitudinal slot therebetween, said slide defining said movable nose on one said slide end extending toward said fixed nose and said slide being slidably mounted in the rail near said rail's other end; a pin transversely fixed in said rail and engaging said longitudinal slot for guiding said slide in longitudinal movement; a threaded bolt welded on the other said slide end; an internally threaded sleeve adjustably engaging said threaded bolt; a guide tube firmly connected to the other end of said rail and slidably supporting said internally threaded sleeve for longitudinal movement; a carrier plate having a nose defined beyond the other end of said rail and off center therewith and having a stop face extending beyond said nose, said carrier plate being fastened to the other end of said rail and to said guide tube; a guide lug for said heald frame holder fixedly attached to said carrier plate; a coil compression spring mounted on said threaded bolt intermediate said slide and said guide tube for biasing said slide and movable nose toward said opposed fixed nose; a toggle link pivotally pinned at one end to said internally threaded sleeve; a double legged clamping lever having two ends, one said end being pivotally pinned to the other end of said toggle link for moving said toggle link into and out of toggle locked association therewith; a cross pin secured to the legs of said clamping lever and positioned therebetween its legs and ends to engage said nose defined on said carrier plate as an axis of rotation of said clamping lever; an abutment piece secured to the other and free end of said clamping lever for limiting the movement of said clamping lever in one direction of rotation to thereby lock said toggle joint and attached said slide against longitudinal movement in a direction away from said fixed notch engaging nose, said clamping lever being limited in rotation in the other direction by its engaged end contacting said carrier plate to unlock said toggle joint to permit the slide and movable nose to be longitudinally moved against said coiled spring bias to release said movable nose from a frame lug notch to disengage the other frame lug notch from said fixed nose.
